UNITED STATES PATENT OFFICE.

JAMES KEITH AND WILLIAM WINSHIP WARDLE, OF LONDON, ENGLAND.

APPARATUS FOR DRYING AND CONDITIONING YARNS, &c.

SPECIFICATION forming part of Letters Patent No. 710,467, dated October 7, 1902.

Application filed January 14, 1902. Serial No. 89,767. (No model.)

To all whom it may concern:

Be it known that we, JAMES KEITH, residing at 27 Farringdon avenue, and WILLIAM WINSHIP WARDLE, residing at 32 Somerfield road, 5 Finsbury Park, London, England, citizens of the United Kingdom of Great Britain and Ireland, have invented certain new and useful Drying-Chambers and Apparatus for Drying and Conditioning Yarns, Fabrics, and other 10 Goods, (for which application for patent has been made in Great Britain, No. 12,389, dated June 18, 1901,) of which the following is a specification.

This invention relates to drying-chambers 15 and apparatus for heating and circulating air therethrough for the purpose of drying and conditioning yarns, fabrics, and other goods; and it comprises improvements in the construction and arrangement of such chambers 20 and apparatus for conveying the goods through the drying-chambers while being acted on by the circulating air and automatically delivering them, whereby the necessity for operators entering the heated chambers is 25 obviated.

In the accompanying drawings, which illustrate the invention, Figure 1 is a vertical longitudinal section of a drying and conditioning chamber and accessories constructed and 30 arranged in accordance with the invention; and Fig. 2 is a longitudinal section of the same, the section being taken on two different planes. Figs. 3 and 4 are detail views at right angles to each other of part of the conveying-band.

The apparatus hereinafter described is capable of drying and conditioning yarns and the like in hank form; but the means for conveying the goods through the drying-chambers is particularly designed for holding woven or other fabrics or garments and for sheets of paper or like flat goods to be dried.

The drying-chamber *a* has vertical sides and a sloping roof *b*, near which a circulating-fan 45 *c* is situated in a vertical wall *f*, extending downward for a short distance and dividing the upper portion of the chamber *a* into two compartments. Heating apparatus, such as a coil of steam or hot-water pipes *d*, is located 50 in proximity to the fan *c* immediately under the sloping roof *b*, and another series of steam-pipes *e* near the bottom of the chamber in

proximity to the fresh-air inlets *g*. Air is drawn, as shown by the arrows, from one side of the vertical wall *f* by the fan *c* and discharged on the other side, the air passing through the heating apparatus *d* to and through between the goods being dried or conditioned, the air so directed, together with fresh air drawn in, being directed toward the lower heating apparatus *e* and thence upward again to the suction side of the fan *c*. The surplus or moist air is discharged by a ventilator *h* on the sloping roof, an exit-passage *i* being provided in the wall of the building 65 for carrying this surplus air to the atmosphere.

The apparatus for conveying the goods to be dried through the drying-chamber *a* consists, as shown by the drawings, of endless 70 bands *j*, passing around rollers *o*, said bands being made up, as shown particularly at Figs. 3 and 4, of chain-links *k*, preferably of T shape, the chain-links *k* being formed with or having attached to them cross laths or blocks 75 *l*, to which holding-clips *m* are jointed, the under side of the band *j* being steadied and guided in side rails *n*. The holding-clips *m* consist of rollers jointed to the blocks, as shown, the arms *p* of the joint being of such 80 length that when the clips *m* are in an approximately horizontal position they rest against the forward side of the adjoining block *l*. The goods are inserted between the clip *m* and the adjoining block *l* by pushing 85 the goods against the rollers *m*, and thereby raising them, the clips on again reaching their normal position engaging and firmly holding the goods, which in the case of sheets of paper or of garments extend transversely of 90 the chamber *a*, as shown at *x*, Fig. 2, from a clip on one band *j* to a clip on the adjacent band *j*.

For convenience of inserting and delivering the goods the rollers *o*, around which the 95 chain-links *k* pass, are fitted in proximity to or without the end walls of the chamber *a*, so that the goods may be placed into clips *m* by the operator, and at the opposite end the goods are automatically delivered as the 100 chain-links *k* ride around the roller *o*, owing to each lath or block *l* in the turning operation moving away from the clip *m*, jointed to the lath or block *l* behind, as shown at Fig. 1.

The blocks *l* are formed with heels *q* to prevent the clips *m* dropping below the horizontal position when the blocks *l* are passing around the rollers *o*.

- 5 The goods are dried by the action of the heated air in their passage through the drying-chamber *a*, and the operator is not under the necessity of entering the chamber, but merely slips up the goods through a doorway
- 10 *r* into the clips *m* at the feeding-in end and may at the same time actuate a hand-wheel *n* on the spindle of the roller *o* to move forward the endless band *j*, carrying the clips *m*, the automatically-delivered goods being periodically removed by a door at the opposite end.
- 15 Having now described the invention, what we claim, and desire to secure by Letters Patent, is—
- 20 1. Means for drying and conditioning yarns fabrics and other goods comprising in combination a drying-chamber having vertical walls and a sloping roof a ventilator in said roof a vertical wall extending downward from the sloping roof and a circulating-fan located in said vertical wall, heating apparatus situated in proximity to the fresh-air inlets and
- 25

close to the discharge side of the fan, an endless-band conveyer passed around rollers for carrying the goods to be dried through the 30 heating-chamber said conveyer being composed of blocks or laths fixed on the links of endless chains, and clips on these blocks adapted to engage and hold the goods and to automatically release them at the discharge 35 end substantially as described.

2. In chambers for drying and conditioning yarns fabrics and other goods, a conveyer for carrying the goods through the chamber composed of an endless band of chain-links passing around roller-blocks secured to said links and rollers jointed to said blocks adapted to engage with and hold the goods while traveling through the chamber and to free the goods at the discharge end of said chamber substantially as described.

In witness whereof we have hereunto set our hands in presence of two witnesses.

JAMES KEITH.
WILLIAM WINSHIP WARDLE.
